V. H. EMERSON.

SOUND RECORD TABLET AND METHOD FOR PRODUCING SAME.

APPLICATION FILED MAY 10, 1916.

1,341,740.

Patented June 1, 1920.

FIRST STEP

Provide disc blank of thin flexible sheet, preferably of a gelatinous material, or of celluloid.

SECOND STEP

Prepare a solution of shellac in alcohol (into which a small portion of acetone may be introduced) and add earthy material of required hardness, such as silicon, barytes or a similar clay.

THIRD STEP

Apply shellac solution as a surface coating to the desired depth upon the flexible disc and permit to dry.

FOURTH STEP

Heat coated disc to a semi-plastic state; then press raised matrix die into the surface thereof.

UNITED STATES PATENT OFFICE.

VICTOR HUGO EMERSON, OF NEW YORK, N. Y., ASSIGNOR TO EMERSON PHONOGRAPH CO., INC., A CORPORATION OF NEW YORK.

SOUND-RECORD TABLET AND METHOD FOR PRODUCING SAME.

1,341,740.

Specification of Letters Patent.

Patented June 1, 1920.

Application filed May 10, 1916. Serial No. 96,490.

To all whom it may concern:

Be it known that I, VICTOR HUGO EMERSON, a citizen of the United States, residing in the city, county, and State of New York, 5 have invented certain new and useful Improvements in Sound-Record Tablets and Methods for Producing Same, fully described and represented in the following specification and the accompanying drawings, forming a part of the same.

My invention relates to sound records and methods of producing the same, and has for an object to improve articles of the class described as to their size, durability and other 15 advantageous qualities, and also to improve the process of making records thereby, while reducing the cost of production thereof.

In the development of the art of making sound records, various methods have been 20 sorted to, among which for example is the forming of the records wholly from homogeneous plastic material. Other processes have been evolved for a like purpose, wherein in the laminated form of record construction 25 is employed, with the result that difficulties have been encountered in working those processes which need not be recited here, but which have largely detracted from the efficiency and economy of that form of construction. Still other methods have been used whereby coatings of so-called record 30 materials have been applied to bases of non-plastic, non-record material, and while some of these last named processes have seemed to 35 succeed somewhat in cheapening the cost, they have not produced records of good character. It is necessary that a substantial thickness of the record be of record material; and where a base of non-record material; 40 and where a base of non-record material is used, good records are difficult to produce. With most of these composite records the construction has been such as to give an article of brittle character, often readily splitting and chipping even with the 45 most careful handling.

To overcome these objections, I have discovered and developed a method whereby a superior form of record may be easily and cheaply produced, an important feature of 50 which consists in the employment of a base that is itself of record material and embodies to a large degree the plastic properties indispensable in forming commercial sound records. Upon this base I plant a layer in 55 integral combination therewith of a record

material also possessed of plastic properties, with the added quality of providing a hard, durable surface, thereby producing a record result which is entirely new in the art.

The drawing is a diagrammatic showing 60 of the steps and their order.

In its broad interpretation my improved process may be described as employing a foundation or base of record material with a thin layer thereon of record material having 65 ingredients differing from the characteristic elements of the base. These two layers I unite firmly and integrally. I usually employ a thermo-plastic base into the surface of which the undulating groove may be impressed, yet incorporating into the surface thus indented to the full depth of the record groove those materials the properties of which reinforce and otherwise augment the 70 wearing and reproducing qualities of the 75 materials constituting the base, so called.

For my purposes I find that such colloidal, flexible, non-fracturing materials as celluloid and gelatin are especially adapted for my base layer of record material; these materials being ductile, pliable, light in weight and possessing the required degree of toughness. All of the foregoing properties are highly conducive to the production of a serviceable record, not only on account of the 80 sound reproducing qualifications of the celluloid and of a properly prepared gelatinous base, which is of course an important reason for their selection, but also for an inherent capacity possessed by similar substances to 85 withstand the wear and tear incident to the repeated handlings attending the use to which sound records are subjected.

The celluloid when employed as a base in forming my record of the disk type, may be 95 used as a very thin sheet to lie flat upon the rotatable table of the sound reproducing mechanism.

The foregoing properties, however, although thus advantageously combined in celluloid, for example, and in gelatin for the purpose outlined, and while important as pointed out, yet do not supply the indispensable characteristics of the material necessary to the making of a highly perfected phonographic record of my invention. First, it is to be noted that the celluloid and gelatin in themselves possess the thermo-plastic quality available for sound record making.

Secondly, celluloid and gelatin possess the property of uniting with certain reinforcing materials, when properly treated, a method for this purpose to be hereinafter more particularly disclosed, with the result that a permanent combination is effected between the materials constituting the base on one hand and the coating of record materials on the other.

10 Thirdly, both celluloid and gelatin share with shellac the glazing property for which shellac is now almost invariably employed in one form and another as the essential ingredient of record materials supplying the 15 hard, unctuous property technically known as the glaze.

While my improved process as pointed out may be employed in connection with base sheet of different materials, the celluloid and 20 gelatin bases having been preferably mentioned, it has been deemed sufficient if the detailed steps thereof be illustrated with reference to celluloid alone, it being understood that other suitable material may be substituted with like effect, and that it is my desire 25 to have broad protection for my process irrespective of the base material employed in the production of records thereby.

Thus, preferably employing celluloid as 30 the base of the product of my improved method, I form a solution of shellac and other elements, to be described presently, in alcohol to which a portion of acetone may be added advantageously in order to accelerate 35 the union of the shellac and other elements constituting the record material, with the base material. Thus by the addition of a comparatively small portion of acetone, the alcohol solution containing shellac and other 40 ingredients are brought more rapidly and intimately into physical and integral contact with the base of suitable material. While the presence of the acetone is thus found most beneficial, I wish to point out 45 in this connection that I do not deem that particular solvent indispensable although highly conducive to the production of a sound record in accordance with my process, which comprises in its essential features the 50 herein described method of dissolving a record material or glaze and applying the dissolved ingredients to a plastic base having record producing properties, such as celluloid, gelatin and like materials.

55 To complete this step of my process I add to the solution thus to be obtained before applying it to the celluloid base, an earthy element such as silica, barytes and a clay of similarly known qualities of hardness, 60 and to those may be added a pigment, for which purpose I find lamp black most satisfactory.

The solution having been thus formed is applied as a thin coat to the surface of a 65 thin sheet of celluloid which has been suit-

ably formed to make a record tablet. The material in solution may be spread upon the celluloid by means of a brush, or by dipping, pouring or in any convenient way known to artisans familiar with the art to which my 70 invention relates.

The layer of record material thus spread upon the celluloid base is not necessarily built up to a given depth, as is required in making records wherein the coating performs the entire function of providing a 75 record medium. In the record which is the product of the present invention, the celluloid base itself being adapted to receive the record groove, as noted above, only requires 80 a sufficient quantity of the coating material to give the surface of the celluloid the required reproducing qualities thereto. However, while this is an important advantage 85 of my improvement, it is obvious that a record produced by my process may have the coating added to a considerable thickness, even to the extent of containing the sound record groove in its entirety, yet, although not a preferable construction, would broadly 90 be within the scope of my invention.

The final step in my process is to convert the blank formed in the manner described, into a sound record, which is accomplished by heating the blank until it becomes sufficiently 95 plastic to receive and retain the imprint in the coated surface thereof, of a record groove formed therein in the usual manner by means of a properly prepared die containing in relief the record of the sounds 100 to be reproduced thereby.

Having described my invention, what I claim is:

1. As an article of manufacture, a sound record having a base of flexible, colloidal 105 material; a record material containing shellac and earthy materials integrally united to the surface of said base; and a sound record groove impressed into said material and said base.

2. As an article of manufacture, a disk sound record comprising a thin sheet of celluloid having upon its surface a thin coating of record material and a sound record groove 110 in the coated surface thereof.

3. The method of producing sound records which consists of applying a thin coat of a solution of shellac and earthy material to the surface of a celluloid record blank.

4. The method of producing sound records 120 which consists of first preparing a record blank composed of celluloid forming a solution of shellac and an earthy material in alcohol and acetone and applying the solution slightly heated to the surface of the 125 celluloid record blank to unite the celluloid and earthy material of the solution integrally with the celluloid.

5. The method of producing sound records 130 which consists of forming a solution of shel-

lac and an earthy material in a solvent such as alcohol or acetone and applying the same to a celluloid record blank, thereupon allowing the solvent to evaporate, and afterward 5 in printing on the surface thereof by means of a suitable die a sound record.

6. As an article of manufacture, a sound record having a thin facing layer of record material containing earthy material and a 10 more flexible backing layer consisting of col-

loidal material possessing record-producing properties.

In testimony whereof, I have hereunto set my hand in the presence of two subscribing witnesses.

VICTOR HUGO EMERSON.
